(57) **CLAIM**

The ornamental design for a hand portable air compressor, as shown and described.

DESCRIPTION

FIG. 1 is a right/front perspective view of a hand portable air compressor showing our new design.

FIG. 2 is a front view thereof.

FIG. 3 is a rear view thereof.

FIG. 4 is a left view thereof.

FIG. 5 is a right side view thereof.

FIG. 6 is a top side view thereof; and,

FIG. 7 is a bottom view thereof.

The broken lines and the areas within the broken lines form no part of the claimed ornamental design.

1 Claim, 6 Drawing Sheets
